UNITED STATES PATENT OFFICE.

WILLIAM W. REED, OF PEORIA, ARKANSAS, ASSIGNOR OF ONE-HALF TO
WILLIAM M. MOORE, OF SAME PLACE.

HOLLOW GRATE-BAR FOR FURNACES.

SPECIFICATION forming part of Letters Patent No. 651,206, dated June 5, 1900.

Application filed March 3, 1900. Serial No. 7,232. (No model.)

To all whom it may concern:

Be it known that I, WILLIAM W. REED, a citizen of the United States, and a resident of Peoria, in the county of Sebastian and State 5 of Arkansas, have invented certain new and useful Improvements in Hollow Grate-Bars for Furnaces, of which the following is a specification.

The object of my invention is to provide an 10 improved water-grate for furnaces comprising hollow grate-bars through which a stream of water is made to flow continuously to not only preserve the grate-bars, but also provide for feeding the boiler with hot water.

15 It is a well-known fact that the ordinary solid grate-bars burn out very rapidly owing to the intense heat of the coals which they support, and it is also well known that the provision of hollow grate-bars and means for 20 causing a flow of water through the same tends to keep the bars at a temperature which will not overheat or injure them. My invention therefore contemplates the production of a 25 grate of this kind and includes devices for utilizing the water which is heated in the 30 grate-bars as feed-water for the boiler; also, an arrangement to provide for shaking the grate and for readily cleaning out the grate-bars.

35 With the above objects in view the invention consists in the construction and combination of parts, as will be hereinafter fully described, and specifically pointed out in the appended claims.

40 In the accompanying drawings, which form a part of this specification, and in which like letters indicate similar parts in both views, Figure 1 is a plan view of a grate for furnaces constructed in accordance with my invention.

45 Fig. 2 is an end view of the grate.

In carrying out my invention the grate proper (designated by the letter A) is composed of a number of hollow grate-bars or straight sections B, and in making up said 45 grate the bars are connected to each other by elbow-couplings C, having flanges c. The grate-bars lie parallel with each other, and each bar is coupled at its ends to the adjoining bar in the manner shown to form a con-

tinuous passage-way or serpentine course for 50 the water.

In coupling the hollow grate-bars bolts c' are passed through the flanges c of the couplings C and plates D interposed between said flanges, the latter forming supporting-arms, 55 as shown.

The grate-bar B at one end of the grate is coupled to a supply-pipe E by means of a vertical pipe F and coupling f, and said vertical pipe is disposed at an inclination, and the 60 couplings are such as to permit of a lateral movement of the grate. To the supply-pipe is connected a pipe G, leading from an inspirator, and beyond pipe G said supply-pipe is provided with a valve or cut-off E'. The 65 grate-bar at the other end of the grate is coupled to a discharge-pipe H by means of an inclined vertical pipe I and couplings h and i, the said discharge-pipe having a T-coupling J, by which a pipe L is connected 70 thereto, and beyond said pipe L the discharge-pipe is provided with a blow-off cock M. The pipe L leads to the boiler (not shown) and is provided with a valve or cut-off l.

75 By providing a series of hollow grate-bars to form the grate of a furnace and connecting said grate-bars to each other and to inlet and discharge pipes, in the manner hereinbefore described, water can be caused to flow slowly 80 through the grate-bars, and thereby keep the grate cool, and the water which is heated in its passage through the grate-bars can be introduced into a boiler as feed-water. In feeding the water to the boiler the cock M is closed and the valve l opened, and in keeping 85 up a circulation of water in the grate-bars the valve l may be closed and the cock M turned to direct the water through the discharge-pipe. In cleaning the grate-bars the valve E' in the supply-pipe is closed and 90 steam is introduced through the pipe G, while the valve l is closed and the blow-off cock M opened. The steam passing through the grate-bars will remove any sediment that might collect therein.

95 From the foregoing description, in connection with the accompanying drawings, it will be seen that I provide a very simple, cheap,

and effective manner of preserving the grate-bars of a furnace, provide for feeding hot water to a boiler, provide for shaking the grate, and also provide for readily and effectively cleaning out the grate-bars. The grate and parts connected thereto and coöperating therewith can be readily applied to an ordinary steam-boiler furnace and will add materially to the effectiveness of the furnace.

Having thus described my invention, what I claim as new, and desire to secure by Letters Patent, is—

1. A grate for steam-boiler furnaces, comprising a number of hollow grate-bars, flanged couplings connecting said grate-bars at their ends to form a serpentine passage-way or grate, and supporting-plates interposed between the couplings and secured thereto; to-

gether with supply and discharge pipes connected to the ends of the grate, as herein shown and described.

2. A grate for steam-boiler furnaces, comprising a series of hollow grate-bars, flanged couplings connecting said grate-bars at their ends to form a serpentine passage-way or grate, supporting-plates interposed between the couplings and secured thereto, vertical pipes coupled to the ends of the grate, and supply and discharge pipes coupled to the lower ends of the vertical pipes respectively, substantially as shown and described.

WILLIAM W. REED.
